SIDE REGISTER GAUGE FOR PRINTING PRESSES

Abel Kluge and Eneval Kluge, St. Paul, Minn., assignors to Brandtjen and Kluge, Inc., St. Paul, Minn., a corporation of Minnesota

Original application December 30, 1932, Serial No. 649,567. Divided and this application July 23, 1937, Serial No. 155,236

10 Claims. (Cl. 101—414)

Our invention relates to improvements in side register gauges for printing presses, this application being a division of our copending application, Serial No. 649,567, filed December 30, 1932.

5 An object of the invention is to provide a simple and durable side register mechanism for bed and platen presses adapted to be readily adjusted during press operation.

Another object of the invention is to provide 10 registering mechanism, as above, adapted readily to be used for both right and left register.

A further object of our invention is to provide 15 a side registering mechanism for a bed and platen press in which a sheet shifting member is carried by the moving platen and a second member, for 20 operating said first member, is mounted on the press frame and adjustable as the platen moves.

With the foregoing and other objects in view, 25 which will appear in the following description, the invention resides in the novel combination and arrangement of parts and in the details of 30 construction hereinafter described and claimed.

In the drawings, Fig. 1 is a vertical sectional view of a bed and platen press equipped with a 35 form of our improved side register mechanism, the structure thereof being shown in side elevation; Figs. 2 and 3 are rear elevational views in detail of the press platen and adjacent frame structure, said views also showing the side register mechanism in detail, an adaptation of the gauge 40 mechanism for register in one direction being shown in Fig. 2 and an adaptation of the gauge mechanism for register in the opposite direction being shown in Fig. 3; Fig. 4 is a detail sectional view taken on line 4—4 of Fig. 3, and Fig. 5 is a detail sectional view taken on the line 5—5 45 of Fig. 3.

Reference being had to the accompanying drawings, it will be seen that the press structure 40 shown includes a frame 30, a platen rocker 38 thereon and a platen 39 carried by said rocker. A suitably driven gear cam wheel 36, mounted on a shaft 37 in the press frame 30, imparts an oscillatory movement to the platen rocker 38 in 45 the customary manner, said gear cam wheel being sheathed by a gear guard 190 incorporated in the press frame structure. A bed 44, supported by legs 46 pivoted on a bed shaft 47 mounted in the frame 30, is connected with the gear cam wheel 36 by means of a side rod 51, a second and similar rod (not shown) being also employed, in the usual manner, to connect said bed with a crank wheel (not shown), mounted on the shaft 37. In its oscillatory movement, the platen 50 55 39 tips back and forth from open position to

impression position, such movement of the platen being accompanied by a relative movement of the bed 44 which brings a form therein against the platen, in its impression position and retracts the bed from the platen in the open position of the latter.

The illustrated side register mechanism includes a rod 182 mounted to slide lengthwise along the lower edge of the platen 39 in bearings 183, 184 secured to the platen, said rod being feathered in bearing 183, as shown, and thereby deprived of rotational movement in said bearings. A roller 185 journaled on the end of the rod 182, at the right hand side of the platen, rolls up and down along an arcuated rail 186 as the platen 39 opens and closes, said roller 185 being yieldingly held against said rail 186 by means of an expansion spring 187 coiled about the rod 182 and compressed between the bearing 184 therefor and a thrust collar 188 secured to said rod. The rail 186 is pivotally mounted medially thereof on a stud 189 projecting from the gear guard 190 and may be angularly swung with respect to the path of movement of the platen 39 from the one of its extreme positions shown in Fig. 2 to the other of its extreme positions shown in Fig. 3. The curvature of said rail 186 is that of an arc struck from the axis about which the platen 39 rocks and the bearing surface 186^a on said rail for said roller 185 is a plane surface. A push-pull adjusting screw 194 journaled in a bearing 195, pivoted by means of a pintle 194^a to the gear guard 190, is threaded in a nut 194^b pivoted on an extension 191 of the rail 186. This push-pull screw 194 is turned by means of a finger piece 194^c, which abuts against one side of the bearing 195. Secured to said screw 194 and abutting against said bearing 195 at the other side thereof is a thrust collar 194^d. As a preliminary measure, this adjusting screw 194 is manipulated to secure, roughly, the desired angular adjustment of the rail 186 and is further manipulated, during the operation of the printing press, to secure finer adjustments of said rail.

For rigidly securing the rail in its various angularly adjusted positions, the extension 191 is formed with a head 192 having a curved slot 192^a therein, the curvature of said slot being that of an arc struck from the axis of the stud 189 upon which the rail is pivotally mounted. A set bolt 193, threaded in a boss 193^a on the gear guard 190 and received in the slot 192^a of said extension head 192, is employed to releasably clamp the extension 191 relative to the gear guard 190.

and thereby rigidly hold the rail 186 in its adjusted positions.

A gauge 196 for right register, and of the construction shown in Fig. 2, may be employed by 5 mounting the same on a block 197 slidably adjustable on the rod 182. This form of gauge has a shank portion 196^a paralleling the rod 182 and an arm 196^b issuing from said shank portion at right angles thereto. Said arm is slotted, as at 10 196^c, and is equipped with the usual slidably adjustable sheet engaging finger 196^d. A gauge 196 for left register, as shown in Fig. 3, may also be mounted on the adjustable block 197, or the well known type of swinging tongue may be employed 15 and operated by the reciprocating rod 182 for engaging a sheet on the platen and shifting it into register.

For right register, as viewed from the front of the press, the gauge 196 and rail 186 will occupy positions, for example, as shown in Fig. 2, while for left register the gauge 196 and rail 186 will occupy positions, for example, as shown in Fig. 3, the position of the rail 186, in either case, being readily adjusted through the medium of 25 the adjusting screw 194 during the operation of the printing press.

Changes in the specific form of our invention, as herein disclosed, may be made within the scope of what is claimed without departing from the 30 spirit of our invention.

Having described our invention, what we claim as new and desire to protect by Letters Patent is:

1. Side registering mechanism for a printing press having a frame, a bed, a rocking platen, 35 and means for rocking the platen into and out of printing relation with respect to the bed, said mechanism comprising a gauge rod slidably mounted on the platen, a rail pivotally mounted medially thereof on the frame of the press, said 40 rail being curved on an arc struck from the axis about which the platen rocks, a follower on the rod engageable with said rail in the various positions assumed by the platen, yielding means acting on the rod to maintain said follower in engagement with the rail as the platen rocks, a gauge mounted on said rod and having a member 45 thereon for engaging and shifting a sheet on the platen, said rail having an extension at one end thereof, a bearing pivoted on the press frame, a nut pivoted to said track extension, a push-pull adjusting screw journaled in 50 said bearing and threaded in said nut, said screw serving upon the manipulation thereof, to swing the rail into any of a number of angular positions skewed with respect to the path of movement of the platen, whereby the gauge rod and the gauge thereon are caused to be shifted more or less in one direction, as desired, upon the closing 55 of the platen.

2. Side registering mechanism for printing 70 press having a frame, a bed, a rocking platen, and means for rocking the platen into and out of printing relation with respect to the bed, said mechanism comprising a gauge rod slidably mounted on the platen, a rail pivotally mounted 75 medially thereof on the frame of the press, said

rail being curved on an arc struck from the axis about which the platen rocks, a follower on the rod engageable with said rail in the various positions assumed by the platen, yielding means acting on the rod to maintain said follower in engagement with the rail as the platen rocks, a gauge mounted on said rod and having a member thereon for engaging and shifting a sheet on the platen, said rail having an extension at one end thereof, a bearing pivoted on the press frame, a nut pivoted to said track extension, a push-pull adjusting screw journaled in said bearing and threaded in said nut, said screw serving upon the manipulation thereof, to swing the rail into any of a number of angular positions skewed with respect to the path of movement of the platen, whereby the gauge rod and the gauge thereon are caused to be shifted more or less in one direction or more or less in the opposite direction, as desired, upon the closing of the 20 platen.

3. Side registering mechanism for a printing press having a frame, a bed, a rocking platen, and means for rocking the platen into and out of printing relation with respect to the bed, said 25 mechanism comprising a gauge rod slidably mounted on the platen, a rail pivotally mounted on the frame of the press, a follower on the rod engageable with said rail in the various positions assumed by the platen, yielding means acting 30 on the rod to maintain said follower in engagement with the rail as the platen rocks, a gauge mounted on said rod and having a member thereon for engaging and shifting a sheet on the platen, an adjusting screw mounted on the press 35 frame and cooperating with said rail to swing the same into any of a number of angular positions skewed with respect to the path of movement of the platen, whereby the gauge rod and gauge thereon are caused to be shifted more or less in one direction, as desired, upon the closing 40 of the platen.

4. Side registering mechanism for a printing press having a frame, a bed and a platen movable forth and back between open sheet receiving 45 position and closed printing position, said mechanism comprising a rail mounted on the press frame, a member movably mounted on the platen and having thereon an element for engaging and shifting a sheet along the platen, said member 50 cooperating with the rail and moved thereby upon movement of said platen, said rail being in skewed relationship with respect to the path of movement of the platen and manually 55 shiftable, during platen movement, from one position to another in such skewed relationship to increase or diminish the extent of movement of said member.

5. Side registering mechanism for a printing press having a frame, a bed and a platen movable forth and back between open sheet receiving 60 position and closed printing position, said mechanism comprising a rail mounted on the press frame, a member movably mounted on the platen and having thereon an element for engaging and shifting a sheet along the platen, said member 65 cooperating with the rail and moved thereby upon movement of said platen, said rail being shiftable into oppositely skewed relationships with respect to the path of movement of the 70 platen for right hand register in one such relationship and left hand register in the other, said rail being manually adjustable in either such relationship during platen movement to increase or diminish the extent of movement of said member. 75

6. Side registering mechanism for a printing press having a frame, a bed and a platen movable forth and back between open sheet receiving position and closed printing position, said mechanism comprising a rail mounted on the press frame, a member movably mounted on the platen and having thereon an element for engaging and shifting a sheet along the platen, said member cooperating with the rail and moved thereby upon movement of said platen, said rail being in skewed relationship with respect to the path of movement of the platen and manually shiftable, during platen movement, from one position to another in such skewed relationship to increase or diminish the extent of movement of said member, and means for releasably securing the rail with respect to the frame in the various selected positions of said rail.
7. Side registering mechanism for a printing press having a frame, a bed and a platen movable forth and back between open sheet receiving position and closed printing position, said mechanism comprising a rail mounted on the press frame and movable thereon to vary its relationship in the press structure, a member movably mounted on the platen, an element actuated by said member for engaging and shifting a sheet along the platen, said member being constantly slidably engaged with the rail and moved thereby in one direction or the other upon movement of said platen in one direction, said rail being manually shiftable, during platen movement, from one position to another and serving, upon being repositioned, to cause the extent of movement of said member to be diminished or increased.
8. Side registering mechanism for a printing press having a frame, a bed and a platen movable forth and back between open sheet receiving position and closed printing position, said mechanism comprising a rail mounted on the press frame and movable thereon to vary its relationship in the press structure, a member movably mounted on the platen, an element actuated by said member for engaging and shifting a sheet along the platen, said member being slidably engaged by the rail and moved in one direction thereby upon movement of said platen in one direction, yielding means acting to maintain said member in sliding engagement with said rail and to reversely move said member upon the reverse movement of said platen, said rail being manually shiftable, during platen movement, from one position to another and serving, upon being repositioned, to cause the extent of movement of said member to be diminished or increased.
9. Side registering mechanism for a printing press having a frame, a bed and a platen movable forth and back between open sheet receiving position and closed printing position, said mechanism comprising guide means mounted on the press frame, a member movably mounted on the platen, an element on said member for engaging a sheet on the platen and shifting such sheet along the platen upon movement of said member, said member following and cooperating with the guide means and moved thereby upon movement of said platen, said guide means being manually shiftable, during the platen movement, from one to another of different relationships in the press structure to cause the sheet registering movement of said member to be increased or diminished.
10. Side registering mechanism for a printing press having a frame, a bed and a platen movable forth and back between open sheet receiving position and closed printing position, said mechanism comprising guide means mounted on the press frame, a member movably mounted on the platen, an element on said member for engaging a sheet on the platen and shifting such sheet along the platen upon movement of said member, said member following and cooperating with the guide means and moved thereby upon movement of said platen, said guide means being manually shiftable, during the platen movement, from one to another of different relationships in the press structure to cause the sheet registering movement of said member to be increased or diminished, and locking mechanism cooperating with said frame and guide means for releasably securing the latter in its various selected relationships.
